STITCHING MECHANISM FOR BUTTON SEWING MACHINES

William T. Maxant, Ayer, Mass.

Original application May 3, 1945, Serial No. 591,656.
Divided and this application March 22, 1951, Serial No. 216,974

2 Claims. (Cl. 112—201)

This application is a division of my prior application filed May 3, 1945, Ser. No. 591,656, for Stop Motion Mechanism for Button Sewing Machines, now Patent No. 2,563,854, granted August 14, 1951.

This invention relates to improvements in button sewing machines, particularly of the character used for sewing flat buttons on work of various kinds, such as strips of cloth, articles of clothing, and the like. It relates more particularly to machines which are used for attaching either two-hole or four-hole buttons thereto by stitching through the eyes of the buttons and the cloth, especially such machines as are operated by power.

The object of this invention is to improve the sewing operation of the machine by providing for proper synchronization between the needle and the rotary looper that cooperates therewith to form the stitches.

This object may be accomplished according to one embodiment of the invention by mounting the looper for rotary adjustment relative to the drive shaft so as to position it properly in timed relation to coact with the needle in forming the stitches. A holder is used to support the looper and is adjustably mounted on the drive shaft. The looper in turn is detachably mounted in the holder. Thus proper adjustment may be provided as desired.

One embodiment of the invention is illustrated in the accompanying drawings in which:

Fig. 1 is a slide elevation of the button sewing machine in which the invention is used; and

Fig. 2 is a detailed longitudinal section therethrough, with parts in elevation and showing the mounting of the looper on the drive shaft.

The machine is adapted for end operation with the operator facing the machine, and with the machine supported on a table, work-bench, or other support, generally designated at S. Accordingly, the machine is constructed with a machine bed designated generally by the numeral 1, adapted to be mounted on or secured to the support S.

A hollow base 2 is connected with the bed 1, by pivotal connections for swinging movement of the base 2, away from the bed 1 to gain access to the operating parts of the machine housed within the base. Normally the base is held in a closed position on the machine bed 1 by a thumb screw 4, which extends through an orifice in one side of the base 2 and engages a recess in a lug attached to the bed 1, which lug extends upwardly within the base 2.

The base frame 2 encloses the principal operating parts of the machine and confines these from entanglement of the cloth therewith, as well as presenting a more attractive appearance to the machine. The base 2 has a forward extension 6 on the front end thereof over which the button clamp is disposed as hereinafter described, which extension is of appreciably less width than the base, to facilitate the manipulation of the articles and access to the button clamp by the operator.

The base 2 also supports the usual upstanding standard 7 fixed on the base, with an arm 8 extending horizontally from the upper end of the standard 7, which arm carries

2

the usual sewing head 9 at the free end thereof. These parts are hollow and communicate at their lower end with the base 2. These parts comprising the standard 7, arm 8, and sewing head 9 are preferably cast integral and either secured rigidly on the base 2 or cast integral therewith. The outer side of the sewing head 9 is initially open but is enclosed by a cover plate 10 which is detachably mounted thereon in the usual manner.

10 The sewing head 9 has the usual needle bar 11 mounted therein and guided at the top through a bushing 12 for reciprocating movement vertically through the head 9. The lower end of the needle bar 11 carries the usual sewing needle 13. The needle bar 11 is adapted to be reciprocated sufficiently far to project the needle 13 into the base extension 6 for cooperating action with sewing instrumentalities contained therein.

20 The machine includes means for reciprocating the needle bar axially, which means is operated by the drive shaft 20 and preferably extends through the hollow standard 7 and arm 8, and into the head 9 where it is operatively connected with the needle bar for reciprocating the latter. This means for operating the needle bar in properly timed relation with the action of the machine is not illustrated in detail but reference may be had to the aforesaid application, Ser. No. 591,656, filed May 3, 1945, now Patent No. 2,563,854, for a more complete description thereof.

25 At the forward end, the drive shaft 20 extends through the bearing block 22, and has fixed thereon a holder 24 which is sleeved over the drive shaft 20 and is secured thereto by set screws 25 which engage in recesses in the periphery of the corresponding portion of the drive shaft 20. The holder 24 carries the usual thread looper 26 fixed thereon by a stub shaft 26' inserted into the end of the holder 24 and secured thereto by a set screw 25', whereby the looper 26 will rotate with the drive shaft 20. The mounting of the looper 26 on the holder 24 permits rotation of the latter relative to the drive shaft 20 for adjustment of the looper 26, so as to time its operation relative to the other operating parts of the machine, particularly the movement of the needle 13 which coacts with the looper 26 to accomplish the stitching action in the manner well-known in the art.

30 The looper 26 is mounted in the base 2 within the extension 6 thereof at a point beneath the needle 13 in position to cooperate therewith to accomplish the desired stitching action. The means for controlling the operation of the stitching cycle, both of the needle and of the looper, are not illustrated in detail since any suitable well-known means may be used for this purpose such as has been set forth in the aforesaid patent application.

35 The usual thread tension devices may be used as indicated generally at 145 and 146, which tension devices may be of any well-known construction and need not be described in detail.

40 The thread is supplied from a spool mounted on a stand generally designated at 147 at the back end of the machine, as shown in Fig. 1. This stand includes a supporting plate 148 and integrally cast flaring sides 149 formed in one integral piece with said plate, so as to extend over the top and down opposite sides of the pulleys 33 and 34. Thus the thread holder also forms a guard for the pulleys and belt as well as to support the thread.

45 The thread holder 147 is supported by brackets 150 secured upon the base 2. An upstanding hook member 151 is carried by the stand 147 and has an eyelet in the upper end thereof in position to overlie the spool mounted on the stand for guiding the thread therefrom.

50 The face plate 10 has the usual eyelets 152 and 153 (Fig. 1) in the upper and lower portions thereof, and an intermediate thread guide generally indicated at 154. A thread guide as shown also at 155 projecting through a

slot in the face plate 10 and carried by the needle bar 11.

Before starting the sewing operation, the material is placed beneath the button clamp upon the cloth plate 92 of the button clamp. This should be done when the button clamp is in its elevated position, which will afford ready access thereto for this purpose. The button is then inserted into the clamping jaws 90, and the button clamp 89 is lowered to the position shown in Fig. 1.

The operator then swings the hand lever 48, which controls the stop motion mechanism. This action frees 10 the shaft 20 for rotation.

The forward movement of the stop motion shaft by the lever 48 slides the belt shifter 36 inwardly which not only shifts the belt from the pulley 34 to the pulley 33, but also releases the brake lining 38 from the face of the pulley 33 which frees this pulley and the shaft connected therewith for rotation by the belt. The drive shaft 20 is then operated by the pulley 33.

The rotation of the drive shaft 20 reciprocates the needle bar 11 through a stroke sufficient to direct the needle downwardly into the base extension 6 for cooperating stitching action with the looper 26 that is rotated by the main shaft 20 on which it is mounted.

While the invention has been illustrated and described in one embodiment, it is recognized that variations and changes may be made therein without departing from the invention as set forth in the claims.

I claim:

1. A looper support for a sewing machine comprising

an operating shaft having a cylindrical end, a cylindrical holder sleeved over said cylindrical end of the operating shaft and rotatably adjustable circumferentially relative thereto, means for securing the holder rigidly in adjusted position to the shaft, said holder having a socket therein in longitudinal axial alignment with the shaft, a rotary looper having a cylindrical projecting shank extending into the socket and axially adjustable therein relative to the holder, and means for securing the shank in the socket in adjusted position.

2. In a sewing machine having an operating shaft having a cylindrical end, the combination with said shaft, of a cylindrical holder sleeved over said cylindrical end thereof and rotatably adjustable bodily relative thereto, a set screw threaded through the holder into engagement with the shaft for securing the holder rigidly in adjusted position relative to the shaft, said holder having a socket in an end thereof in axial alignment with the shaft, a rotary looper having a cylindrical projecting shank extending into the socket and axially adjustable therein relative to the holder, and a set screw threaded through a side of the holder into engagement with the shank for securing the shank in the socket in adjusted position.
